HOLDER FOR LOOPED MATCH BOOKS

David O. Ford, Colonial Heights, Va., assignor to
Joseph Mills Hanson, Colonial Heights, Va.

Application August 15, 1938, Serial No. 225,032

2 Claims. (Cl. 206—19.5)

This invention relates to match holders or supports and more particularly to a holder especially designed to receive and support a looped match book of the type shown and described in my prior United States patent issued to me on December 12, 1939, under No. 2,183,096.

The object of the invention is to provide a match holder of simple and inexpensive construction capable of being readily attached to an automobile steering wheel, ash tray, desk stand, wall or other article or support and by means of which a looped book of matches may be held in a convenient position to permit ready severance and ignition of the individual matches of the book when desired.

A further object of the invention is to provide a match holder having means for attachment to a support and provided with an overhanging transversely curved supporting table adapted to slidably and detachably engage the looped cover of a match book.

A further object of the invention is to form the opposite edges of the overhanging table or support with inwardly extending flanges to prevent cutting or severing the looped portion of the match book when applying the book to or removing said book from the supporting table, said flanges also serving as guides for a removable card bearing suitable indicia which, if desired, may be rendered visible through an opening in the supporting table when the match book is removed therefrom.

A still further object of the invention is generally to improve this class of devices so as to increase their utility, durability and efficiency.

In the accompanying drawings forming a part of this specification and in which similar numerals of reference indicate corresponding parts in all the figures of the drawings:

40. Figure 1 is a perspective view of a holder for supporting a looped match book and showing the device applied to one of the spokes of an automobile steering wheel.

Figure 2 is a transverse sectional view taken 45 on the line 2—2 of Figure 1, the match book being shown in dotted lines.

Figure 3 is a longitudinal sectional view, the match book being omitted.

Figure 4 is a plan view of the blank from which 50 the match holder or support shown in Figure 1 is constructed.

Figure 5 is a front elevation of a match book adapted to be supported on the holder and showing the same in open position and before it is 55 looped.

Figure 6 is a perspective view illustrating a modified form of holder.

Figure 7 is a side elevation showing the support illustrated in Figure 6 in position on a wall or other suitable support.

Figure 8 is a plan view of the blank from which the support shown in Figure 6 is formed, and

Figure 9 is a perspective view showing the looped match book holder or support applied to an ash tray.

The improved holder forming the subject-matter of the present invention is principally designed for supporting a match book of the construction shown in my prior patent, said match book comprising a flexible cover or carrier 5 having one end thereof provided with a transverse slot 6 and its other end folded to form a securing flange 7 for the match splints, indicated at 8. The flange 7 is coated with suitable ignition material 9, and the upper or free end of the flange 10 is provided with spaced notches 10, said notches being intersected by vertical perforations or weakened portions 11 to form a locking lip 12.

The holder for supporting the looped match book may be constructed of any suitable material 25 and in the form illustrated in Figure 1 of the drawings is preferably stamped from a single metal blank having one end thereof provided with spaced parallel fold lines 13 defining outer flanges 14 and an intermediate supporting table 15.

The metal at one end of the supporting table 15 is reduced in width to form a connecting neck 16, the opposite side edges of which are inclined at 17 and merge into a transversely enlarged portion 18, there being notches 19 in said 30 enlarged portion and defining spaced spring clamping fingers 20. The blank is also provided with spaced fold lines 21 at the opposite ends of the neck 16 to facilitate folding or shaping the blank into proper form.

In fashioning the blank 40 into a holder, the portion 18 of the blank is first bent to produce a spring attaching clip 22 adapted to frictionally engage one of the spokes 23 of an automobile steering wheel, indicated at 24.

The neck 16 is then bent at right angles to the clip 22 and the portion 15 of the blank extended longitudinally in spaced parallel relation to the clip 22 to form the supporting table, the flanges 14 being bent downwardly and inwardly in spaced 45 relation to the lower surface of the supporting table to form a pocket 26 for the reception of a removable card 27. The pocket 26 may be used either for receiving an oil check card or a card bearing suitable advertising indicia, the latter being visible through an opening 28 formed in 50

the table to receive a card 27.

Figure 3 is a longitudinal sectional view, the match book being omitted.

Figure 4 is a plan view of the blank from which 55 the match holder or support shown in Figure 1 is constructed.

Figure 5 is a front elevation of a match book adapted to be supported on the holder and showing the same in open position and before it is 55 looped.

the supporting table 15, as best shown in Figure 3 of the drawings.

In using the device, the holder is fitted about one of the spokes of an automobile steering wheel 5 and in which position it will be retained by the inherent resiliency of the clamping fingers 20. The cover of the book 5 is then bent rearwardly and the locking lip 12 inserted within the transverse slot 6, thus forming a resilient loop, indicated at 29. The loop of the match book is then slidably mounted on the supporting table from the outer or free end thereof and said match book pressed rearwardly until the adjacent edge thereof bears against the neck 16 of the holder 15 which neck constitutes a stop to prevent further rearward movement of the holder on the supporting table. Owing to the resiliency of the loop 29 of the match book, said match book will frictionally engage the supporting table and prevent the match book from becoming accidentally detached therefrom due to vibration or other cause when the automobile is traveling. It will here be noted that the flanges 14 not only serve to prevent cutting or severing the material constituting the loop of the match book when inserting the match book on and removing the match book from the supporting table but also from a pocket for the reception of the card 27. When the match book is positioned on the supporting table in the manner stated, the individual match splints may be readily detached from the book when desired and said match splints ignited by rubbing the heads of the splints over the ignition material 9, as will be readily understood. When the book of matches has been exhausted, the loop of the exhausted book may be readily removed from the supporting table and a new book of matches quickly positioned thereon. By means of this holder a book of matches may be detachably supported on the steering wheel of an automobile and in a convenient position to permit the driver of the automobile to obtain a match whenever desired without the necessity of removing his or her hand from the steering wheel and reaching in to a compartment of the automobile or elsewhere for said match.

In Figures 6 to 8 inclusive of the drawings, there is illustrated a modified form of the invention particularly adapted for attachment to a wall, restaurant booth or other stationary fixture or support. In this form of the device, the opposite sides of the supporting table 30 are preferably inclined or beveled, at 31, to further assist in preventing cutting of the match book loop and the reduced neck 32 is formed integral with a transversely disposed attaching strap 33 having perforations 34 formed therein for the reception of screws or similar fastening devices 35, by means of which the holder may be secured in either a vertical or horizontal plane to a wall or other support, indicated at 36. The operation of this form of the holder is identical with that shown in Figure 1 and further detailed description thereof is deemed unnecessary.

If desired, the match book holder may be at-

tached to or formed integral with an ash tray, desk stand or the like, and in Figure 9 of the drawings, there is illustrated an ash tray 37 of conventional construction having a post or standard 38 at one end thereof and to which is secured or integrally formed an overhanging match book holder, indicated at 39. In this form of the device, the match book holder 39 is solid and provided on its opposite sides with beveled edges 40 to prevent cutting or severing the loop 10 of the match book when positioning the match book on or removing the match book from the holder. If desired, however, a hollow supporting table of the construction shown either in Figure 1 or Figure 6 of the drawings may be attached to the post or standard 38 of the match tray. A device constructed in accordance with the present invention can be conveniently supported on a wall or other stationary fixture, in a home near a gas range or over a stove, in commercially built trailers, filling stations, smoking rooms and ladies' lounging rooms or wherever it is desired to have book matches readily accessible for detachment and ignition of a match when desired.

It will, of course, be understood that the holders may be made in different sizes and shapes and constructed of any suitable material without departing from the spirit of the invention.

Having thus described the invention, what is claimed as new is:

1. A one-piece support for match books comprising a base, an arm extending substantially at right angles therefrom, an elongated flat supporting member integral with said arm and extending substantially parallel to and in spaced relation to said base and in the same general direction as the base, said supporting member having its opposite side edges bent inwardly towards each other and towards the base, said supporting member being adapted to have a match book wrapped therearound, the flanges functioning to support a card and the arm constituting a stop, and means for securing the base to a support.

2. A one-piece support for match books comprising an elongated base having its side portions bent to form jaws for gripping a support and detachably holding the base thereon, an arm extending at substantially right angles from one end of said base, an elongated supporting member having one end integrally united with the upper end of said arm, said supporting member extending from the arm in the same direction as the base and disposed in spaced and substantially parallel relation to the base, a sight opening being formed in the supporting member, and opposite side portions of said supporting member being bent to form flanges extending inwardly and towards the base, the supporting member being adapted to have a match book cover wrapped therearound, and said flanges functioning to support a card under the supporting member in position to be seen through the sight opening.

DAVID O. FORD. 65
